UNITED STATES PATENT OFFICE

145,695

DESIGN FOR AN ELECTRIC STOVE

Raymond Heer, Chicago, Ill., assignor to General Consumer Products, Inc., Chicago, Ill., a corporation of Illinois

Application December 15, 1945, Serial No. 124,769

Term of patent 14 years

(Cl. D81—10)

To all whom it may concern:

Be it known that I, Raymond Heer, a citizen of the United States, residing at Chicago, Cook County, Illinois, have invented a new, original, and ornamental Design for an Electric Stove, of which the following is a specification, reference being had to the accompanying drawing, forming a part thereof.

Figure 1 is a side elevational view of an electric stove embodying my new design;

Figure 2 is a vertical transverse section of the upper portion of the stove;

Figure 3 is a side elevational view as viewed from the left or right of Figure 1; and

Figure 4 is a plan view thereof.

The essential features of the design reside in the portions shown in full lines.

I claim:

The ornamental design for an electric stove, as shown and described.

RAYMOND HEER.
